UNITED STATES PATENT OFFICE

2,353,024

DOUGHNUT MACHINE

Stephen A. Gardner, Minneapolis, Minn., assignor to Dough-King, Inc., Minneapolis, Minn., a corporation of Minnesota

Application September 8, 1941, Serial No. 409,979

6 Claims. (Cl. 99—406)

My invention relates to ejectors for doughnut machines and particularly to ejectors utilizing a number of inclined blades extending into the cooking liquid, certain of said blades being adapted to be alternately moved in relation to the others to remove the doughnuts from the machine.

An object of the invention resides in utilizing a revoluble member having a number of cranks and in supporting all of the blades on said revoluble member and in supporting said blades in a manner such that the blades may be easily removed therefrom.

Another object of the invention resides in providing a construction for attaching the blades to the cranks so that said blades will not become accidentally disengaged from the cranks.

A still further object of the invention resides in providing an ejector in which doughnuts will not readily become engaged under the ends of the cranks to unseat the blades.

Another object of the invention resides in constructing certain of the blades with a longitudinally extending slot open at the outer end and provided with a socket connected therewith and adapted to receive a pin of the crank.

An object of the invention resides in arranging said socket at the inner end of the slot.

An object of the invention resides in providing a chute for receiving the doughnuts discharged from the machine and in arranging alternate blades in a stationary position with the ends thereof extending in close proximity to the chute to form a continuous conduit for the doughnuts.

Another object of the invention resides in constructing said revoluble member with a number of crank shaft sections and in supporting the stationary blades on said crank shaft sections.

Other objects of the invention reside in the novel combination and arrangement of parts and in the details of construction hereinafter illustrated and/or described.

In the drawings

Fig. 1 is a plan sectional view of a doughnut machine illustrating an embodiment of my invention.

Fig. 2 is an elevational sectional view taken on line 2—2 of Fig. 1.

Fig. 3 is a view similar to Fig. 2 of a portion of the structure disclosed therein and drawn to a greater scale.

In the use of ejectors for doughnut machines employing two sets of blades having relative movement, it has been found that where the

same are connected to the crank pins by slots extending through a lateral edge of the blades, that where the friction to the downward movement of the blades is appreciable, occasionally the blades become disengaged from the crank pins. It has also been found that frequently doughnuts become caught under the ends of the blades and particularly between the blades and the discharge chute or trough and thus become injured. The instant invention provides a construction by means of which these disadvantages may be overcome and at the same time, permits of easily and quickly removing the blades from the doughnut machine when the occasion arises.

For the purpose of illustrating my invention, I have shown a doughnut machine which is indicated in its entirety by the reference numeral A and which consists of a case 10 constructed with end walls 11 and 12 and said walls 13 and 14 connected therewith. The case A includes uprights 15 disposed at the outer corners of the same, which extend throughout the height of the case and to which the various walls are attached.

Within the case 10 is disposed a cooking kettle 18 which is preferably of cast material and which is constructed with a bottom 19 and with vertical walls 21 extending upwardly therefrom. The vertical walls are connected at their upper ends with upper walls 22 and the various walls are so arranged as to form a channel 23 which extends throughout the major portion of the kettle and which provides a way along which the doughnuts may travel. The kettle 18 has a corner of the same removed as indicated at 24, leaving a main portion 25 of the width of the case and of a length equal to about two-thirds of the length of the same. This construction also provides an extension 26 to the kettle which extends up to the end wall 12. The kettle 18 is supported from the case 10 in any suitable manner.

The channel 23 is arranged to provide a straight run 32 which commences in close proximity to the wall 12 and follows along the wall 14. The channel 23 at the end of the run 32 makes a curve 33 which leads into another straight run 34 following along the wall 11. At the end of this run, the channel has another curve 35 which leads into still another straight run 36 which follows along the wall 13. At the end of the run 36, the channel is constructed with a loop 37 which communicates with an S-shaped run 38. The latter run has an end por-

tion 40 and communicates with a straight run 39 which is parallel with the run 32. The run 39 discharges into a reservoir 41 which is merely an enlargement of said run. From this reservoir, a short run 42 is provided which forms part of a loop 43 connected to the beginning of the run 32.

The major portion 25 of kettle 18 is enclosed by means of a hood 44. This hood utilizes the uprights 15 at the end wall 11 and other uprights 45 which are attached to the case 10 at the locality of the end of the major portion 25 of the kettle formed by the corner 24. Between these uprights are provided glass panels 46 which are slidably supported in guides 47 whereby the said panels may be raised or removed. The hood also includes a top 50, which is carried by the uprights 15 and 45. The hood is so designed that the same encloses the runs 33, 34, 35, 36, 37, 38 and the major portions of the runs 39 and 32, leaving part of the reservoir 41 and the loop 43 disposed outwardly of the hood.

In the reservoir 41 is provided a vertical tubular duct 48, which is connected at its lower end to the bottom of the reservoir 41. In this duct is disposed a propeller or elevator 49 which is mounted on the armature shaft of a motor 51. The duct 48 communicates at its upper end with the run 42 of channel 23, thus discharging the cooking liquid from the duct 48 and into the run 42 of the channel from which it flows throughout the course of the channel and is returned to the reservoir 41.

At the lowermost portion of the reservoir 41 is arranged a clean-out 52 which also serves as a sump for collecting crumbs and other solid material formed in the operation of the machine. This construction, forming no particular feature of the invention, has not been illustrated in detail.

Overlying the extension 26 of the kettle 18 is a plate 58 which covers a part of the reservoir 41, the duct 48, the runs 42 and 43 and a portion of the run 32 of the channel 23. This plate is attached to the case A in any suitable manner.

Situated at the beginning of the run 32 of channel 23 is a doughnut former 53 which comprises a receptacle 54 for dough and a cutter 55 connected therewith. Such construction being well known in the art, will not be described in detail in this application. The cutter 53 is operated from a shaft 56 which is journaled in a bearing 57 attached to the plate 58 and which is driven by a suitable motor and transmission enclosed within a transmission housing 59. Inasmuch as the drive mechanism for the shaft 56 does not form a feature of the invention, the same has not been illustrated. It will thus become readily apparent that doughnuts extruded from the former 53 are deposited in the flowing cooking liquid which travels along the run 32 of channel 23 in the direction of the arrow.

In the run 36 of channel 23 is arranged a twisted tubular turner 61. This turner inverts the doughnuts after the same have been cooked a predetermined length of time so that the doughnuts may be properly cooked on both sides thereof.

In the run 34 of the channel 23 and in the portion 40 of run 38 of said channel are located two control devices 62 and 63. These control devices extend into the cooking liquid and are alternately moved from obstructing to unobstructing position to allow the doughnuts to pass one at a time. These devices are operated by means of

5 a shaft 64 driven from the transmission within the case 59. By means of these control devices, the length of the cooking period of the doughnuts on both sides thereof is accurately controlled. Since these devices do not form any particular feature of the invention, the same have not been illustrated in detail.

The invention proper includes an ejector 73 which is disposed in the run 39 of channel 23. 10 This ejector comprises a revoluble member 70 which includes a shaft 75 which is constantly driven from the transmission within the housing 59. This shaft has mounted on it a plurality of cranks 76, all of which extend the same direction from the axis of the shaft. The cranks 76 have crank pins 77 which are connected together by means of bars 78. These bars in turn are connected to pins 79 which are concentrically disposed with reference to the shaft 75 and which 15 form shaft sections constituting a continuation of the shaft 75. In conjunction with the revoluble member 70, two sets of toothed blades 81 and 82 are employed, which extend in inclined relation partly above and partly below the level of the cooking liquid. Both sets of blades are supported at their upper ends by the revoluble member 70 and are supported at their lower ends upon an inclined rest 83 which is mounted on the bottom 19 of receptacle 18 in the portion of the run 39 connected with the portion 40 of run 38.

20 The blades 81 are constructed at their upper ends with heads 84 which are formed with slots 85. These slots have longitudinally extending portions 87 which open outwardly through the ends 86 of said blades and with transversely extending portions 88 which form sockets for the reception of the pins 77 of the cranks 76. The ends 86 of these blades are curved as designated at 89 to prevent endwise engagement with the doughnuts and injury thereto. The blades 82 are 25 constructed similarly to the blades 81 and are formed with heads 91 at their upper ends. These heads have transversely extending slots 90 there- 30 in which open through the lower edges of said blades and which form sockets in which the crank shaft sections 79 are pivoted. The heads 91 have depending portions 92 which extend down to the bottom 93 of a trough 94 from which the doughnuts are 35 discharged out of the machine. The bottom 93 of the said trough rests upon the plate 58 and is constructed with two side walls 95 which extend along the kettle and assist in maintaining the doughnuts supported upon the blades 40 81 and 82.

45 In the operation of the invention, the blades 82 remain stationary, the shaft sections 79 rotating in the sockets formed by the slots 90. The blades 81 are manipulated by the crank 76 in a manner such that the doughnuts floating along the level of the cooking liquid are engaged by the said blades, raised and moved longitudinally upwardly within the trough 94. When the revoluble member has turned sufficiently, the doughnuts are deposited upon the blades 82 and the blades 81 return to a lower position in which the doughnuts may be again engaged and further moved along the trough 94. Whenever it becomes necessary to clean the machine, the blades 50 81 are first raised sufficiently to disengage the pins 77 from the sockets 88 and then the said blades are moved lengthwise, the longitudinal portions 87 of slots moving along the pins until the pins are freed from the ends 86 of said blades.

55 The advantages of my invention are manifest.

Injury to the doughnuts in their travel along the ejector is eliminated. The device will not readily get out of order. The blades are easily removed for cleaning and to give access to the cooking kettle. My improved ejector may be constructed without additional expense.

Changes in the specific form of my invention, as herein disclosed, may be made within the scope of what is claimed without departing from the spirit of my invention.

Having described my invention, what I claim as new and desire to protect by Letters Patent is:

1. In a doughnut machine, a kettle having a channel along which the doughnuts travel during cooking and formed with a discharge run, a revolute member at the discharge run having crank means and shaft means, two sets of interdisposed blades within said discharge run, said blades being disposed at an angle with respect to the surface of the cooking liquid and extending partly beneath and partly above the surface of the cooking liquid, one set of said blades being stationary and being supported at their outer ends by said shaft means, the other set of blades being pivoted at their outer ends to said crank means and being moved thereby relative to said stationary blades and means for further supporting said blades.

2. In a doughnut machine, a kettle having a channel along which the doughnuts travel during cooking and formed with a discharge run, a revolute member at the discharge run having a plurality of spaced cranks connected together by a plurality of shaft sections, two sets of interdisposed blades within said discharge run, said blades being disposed at an angle with respect to the surface of the cooking liquid and extending partly beneath and partly above the surface of the cooking liquid, one set of said blades being stationary and being supported at their outer ends by said shaft sections, the other set of blades being pivoted at their outer ends to said cranks and being moved thereby relative to said stationary blades and means for further supporting said blades.

3. In a doughnut machine, a kettle having a channel along which the doughnuts travel during cooking and formed with a discharge run, a discharge trough in said discharge run having a bottom, a revolute member having crank means and shaft means, said revolute member being disposed with the crank means above the bottom of said trough, two sets of interdisposed blades within said discharge run, said blades being disposed at an angle with respect to the surface of the cooking liquid and extending partly beneath and partly above the surface of the cooking liquid, one set of said blades being stationary and being supported at their outer ends by said shaft means, the other set of blades being pivoted at their outer ends to said crank means and being moved thereby relative to said stationary blades, said stationary blades having

depending portions at their outer ends extending downwardly toward the bottom of the trough and means for further supporting said blades.

4. In a doughnut machine, a kettle having a channel along which the doughnuts travel during cooking and formed with a discharge run, a discharge trough in said discharge run having a bottom, a revolute member having a plurality of spaced cranks connected together by a plurality of shaft sections, two sets of interdisposed blades within said discharge run, said blades being disposed at an angle with respect to the surface of the cooking liquid and extending partly beneath and partly above the surface of the cooking liquid, one set of said blades being stationary and being supported at their outer ends by said shaft sections, said blades having depending portions at their outer ends extending downwardly toward the bottom of the trough, the other of said blades being pivoted at their outer ends to said cranks and being moved thereby relative to said stationary blades and means for further supporting said blades.

5. In a doughnut machine, a kettle having a channel along which the doughnuts travel during cooking and formed with a discharge run, a discharge trough in said discharge run having a bottom, a revolute member having crank means disposed above the bottom of said trough, two sets of interdisposed blades, said blades being disposed at an angle with respect to the surface of the cooking liquid and extending partly beneath and partly above the surface of the cooking liquid, one set of blades being supported at their outer ends by said crank means, the other set of blades being stationary, means for supporting the stationary set of blades at their outer ends, said stationary blades having depending portions at their outer ends extending downwardly toward the bottom of the trough and means for further supporting said blades.

6. In a doughnut machine, a kettle having a channel along which the doughnuts travel during cooking and formed with a discharge run, a discharge trough in said discharge run having a bottom, a revolute member having crank means disposed above the bottom of said trough, two sets of interdisposed blades, said blades being disposed at an angle with respect to the surface of the cooking liquid and extending partly beneath and partly above the surface of the cooking liquid, one set of blades being supported at their outer ends by said crank means, the other set of blades being stationary, means for supporting the stationary set of blades at their outer ends, said stationary blades having depending portions at their outer ends extending downwardly toward the bottom of the trough and arranged with their uppermost surfaces inclining in a direction opposite to the direction of inclination of the blades proper, and means for further supporting said blades.

STEPHEN A. GARDNER.
